UNITED STATES PATENT OFFICE.

GEORGE TOLK AND ALVIN H. ROSENBAUM, OF BROOKLYN, NEW YORK.

DESIGN FOR A TELEPHONE ATTACHMENT CASING.

Application filed January 18, 1924. Serial No. 8,342. Term of patent 3½ years.

To all whom it may concern:

Be it known that we, GEORGE TOLK and ALVIN H. ROSENBAUM, both citizens of the United States, and residents of New York city, borough of Brooklyn, in the county of Kings and State of New York, have invented a new, original, and ornamental Design for Telephone Attachment Casings, of which the following is a specification, reference being had to the accompanying drawings, forming a part thereof, and of which—

Figure 1 is a front perspective and Fig. 2 is a rear perspective of a telephone attachment casing showing our new design.

We claim:

The ornamental design for a telephone attachment casing as shown.

GEORGE TOLK.
ALVIN H. ROSENBAUM.
